Term of patent 3½ years

Int. Cl. D13—03

U.S. Cl. D26—1 A

FIG. 1

FIG. 2

FIG. 3

FIG. 1 is a perspective view of an electrical plug showing my new design;

FIG. 2 is a left end elevational view thereof; and

FIG. 3 is a right end elevational view thereof.

The side opposite to that shown in FIG. 1 is a mirror image thereof.

The broken line showings in FIGS. 1 and 3 are for illustrative purposes only, and are not part of my claimed design.

I claim:

The ornamental design for an electrical plug, as shown and described.
